United States Patent

Des. 239,916
Patented May 18, 1976

239,916

HOLDER FOR SOLDERING INSTRUMENT OR THE LIKE

William S. Fortune, 14250 Dearborn St.,
Panorama City, Calif. 91402

Filed May 5, 1975, Ser. No. 574,463

Term of patent 14 years

Int. Cl. D8—05

U.S. Cl. D8—71

Fig. 1

Fig. 2

Fig. 3

Fig. 4

Fig. 5

FIG. 1 is a left side elevational view of a holder for soldering instrument or the like embodying my new design;

FIG. 2 is a right side elevational view thereof;

FIG. 3 is a plan view thereof;

FIG. 4 is a front elevational view thereof; and

FIG. 5 is a rear elevational view thereof.

I claim:

The ornamental design for a holder for soldering instrument or the like, substantially as shown and described.
